US00D977968S

(12) **United States Design Patent** (10) Patent No.: **US D977,968 S**
 Sollie et al. (45) Date of Patent: ** *Feb. 14, 2023

(54) **BOX**

- (71) Applicant: **Pratt Corrugated Holdings, Inc.**, Brookhaven, GA (US)
- (72) Inventors: **Greg Sollie**, Sharpsburg, GA (US); **Shifeng Chen**, Newport News, VA (US); **Randy Ball**, Peachtree City, GA (US)
- (73) Assignee: **Pratt Corrugated Holdings, Inc.**, Brookhaven, GA (US)
- (*) Notice: This patent is subject to a terminal disclaimer.
- (**) Term: **15 Years**
- (21) Appl. No.: **29/804,168**
- (22) Filed: **Aug. 18, 2021**

(57) **CLAIM**

We claim the ornamental design for a box, as shown and described.

DESCRIPTION

FIG. 1 is a perspective view of a box in an open configuration.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a perspective view of the box in a partially closed configuration; and,

FIG. 9 is a top plan view of the box in a flattened configuration.

Those features shown in broken lines form no part of the claimed design.
